US00D984775S

(12) **United States Design Patent** (10) **Patent No.:** **US D984,775 S**
Wallner et al. (45) **Date of Patent:** **** Apr. 25, 2023**

(54) **COMBINED LIFT VEHICLE AND CHASSIS**

(71) Applicant: **Terex South Dakota, Inc.**, Watertown, SD (US)

(72) Inventors: **Maxwell Elliot Wallner**, Watertown, SD (US); **Xiaocheng Yang**, Watertown, SD (US); **Kai Wang**, Watertown, SD (US); **Ye Huang**, Watertown, SD (US); **Zachary Samuels Fung**, Watertown, SD (US)

(73) Assignee: **Terex South Dakota, Inc.**, Watertown, SD (US)

(**) Term: **15 Years**

(21) Appl. No.: **29/728,525**

(22) Filed: **Mar. 19, 2020**

(51) LOC (14) Cl. **12-05**

(52) U.S. Cl.

(57) **CLAIM**

The ornamental design for a combined lift vehicle and chassis, as shown and described.

DESCRIPTION

FIG. 1 is a front perspective view of a combined lift vehicle and chassis showing the first embodiment of our design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is a front perspective view of a combined lift vehicle and chassis according to a second embodiment;

FIG. 10 is a rear perspective view thereof;

FIG. 11 is a left side view thereof;

FIG. 12 is a right side view thereof;

FIG. 13 is a rear view thereof;

FIG. 14 is a front view thereof;

FIG. 15 is a top view thereof; and,

FIG. 16 is a bottom view thereof.

The broken lines shown in the figures are for the purpose of illustrating portions of the combined lift vehicle or chassis and form no part of the claimed design.

1 Claim, 16 Drawing Sheets
